 tion of Ohio

Application November 16, 1950, Serial No. 195,949

6 Claims. (Cl. 312—111)

1

This invention relates to a shell for a filing cabinet, storage cabinet or the like, to the blank from which it is formed, to the method or methods of forming the shell from the blank, and to certain elements such as drawer stops, stacking lugs, etc., that may advantageously be structurally associated with the shell.

More particularly, the invention relates to a fiber board shell made up of interconnected top, bottom and side panels. In a preferred embodiment of the invention, the shell not only is of fiber board but of internally corrugated fiber board in which the corrugations parallel the longitudinal axis of the shell. Preferably, the shell is chemically impregnated, as with sulphur, in order to stiffen it, which can best be done after the shell has been fully assembled; in such case, advantages respecting the completeness of penetration of the chemical or chemicals result from the fact that the corrugations and major fold lines extend in the same general direction.

Objects of the invention are to provide a shell of this kind that is simple, inexpensive to fabricate, but nevertheless sturdy enough to resist the stresses to which the shell is likely to be subject in use. Other objects of the invention have to do with the incorporation in the shell of drawer stops which, as hereinafter explained, are preferably formed integrally with the blank itself. Other objects of the invention are to provide stacking lugs and cooperating recesses whereby two or more shells may be stacked in a manner preventing sliding of an upper shell on a lower shell. Still other objects of the invention contemplate the elimination of the extraneous reinforcing elements, usually of metal, which in the past have ordinarily been necessary to prevent collapse of fiber board shells under load.

These and other objects and advantages of the invention will be apparent from the description which follows and from the accompanying drawings.

In such drawings, which show a preferred embodiment of the invention, Figure 1 is a perspective of a three-compartment cabinet constructed in accordance with the present invention; Figure 2 is a perspective of the same cabinet with the drawers removed to show the interior construction; Figure 3 is a detail on an enlarged scale showing one of the drawer stops as seen in perspective but from an angle different from that characterizing Figures 1 and 2; Figures 4 is a development or plan of a blank from which may be formed a shell of the kind used in each of the compartments of the cabinet shown

2

in Figures 1 and 2; Figure 5 is a similar view of a portion of the blank of Figure 4, but at a somewhat later stage; Figure 6 is an isometric view of the blank, but at a stage subsequent to that illustrated in Figure 5, as it is being folded on itself to form the shell; and Figure 7 is a fragmentary longitudinal section through two stacked compartments employing shells of the kind to which the invention relates, the section showing the parts at the bottom portion of an upper shell A and the parts at the top portion of a lower shell B.

As indicated in Figure 1, a fiber board cabinet, such as a filing cabinet, storage cabinet or the like, may be made up in accordance with the teachings of the invention from one or more fiber board compartments of which three, designated 2, 3 and 4, appear in the figure. Compartments 2, 3 and 4 are identical, interchangeable and constructed in the manner described hereinafter so as to facilitate stacking of the compartments on each other. The three compartments embody fiber board shells 5, 6 and 7, respectively, along with cooperative fiber board drawers 8, 9 and 10. The latter are provided with recessed bail handles 11, 12 and 13 and wire card holders 14, 15 and 16, all as shown in Figure 1. As appears from Figure 2, compartments 2, 3 and 4 are provided with drawer stops 17, 18 and 19, respectively, there being one or more such drawer stops (two being shown) structurally associated with the top of each of the shells and more particularly with cuff portions 20, 21 and 22 thereof.

Preferably, shells 5, 6 and 7 are made from flat sheets of corrugated fiber board in which the corrugations 23 parallel the intended longitudinal axes of the shells. As indicated in Figure 4, the blank from which such a shell is formed is generally rectangular in shape. It is divided by score lines into four principal panels, 25, 26, 27 and 28. Respectively, these panels form the bottom, left side, top, and right side of a shell of the type shown in Figure 2. The dimensions of panels 25, 26, 27 and 28 will of course determine the dimensions of the shell, which in a typical case will be somewhat wider than it is high and somewhat longer than it is wide.

Attached to the long side of bottom panel 25 opposite that to which side panel 26 is attached is a reinforcing panel 29. Among other things, it is characterized at its forward or front end by a polygonal cut-away portion defined by a squared-off edge 30 and a contiguous angled edge 31. Reinforcing panel 29 is separated from bot-

tom panel 25 by score line *a*, side panel 26 is separated from bottom panel 25 by score line *b*, top panel 27 is separated from side panel 26 by score line *c*, and side panel 28 is separated from top panel 27 by score line *d*.

Score lines *a*, *b*, *c* and *d* are on the near side of the blank as seen in plan in Figure 4; i. e., on the side of the blank that is to form the inside of the erected shell.

At the rear or back ends of panels 25, 26, 27 and 28 and separated from them by score lines *e*, *f*, *g* and *h*, respectively, are four rectangular extensions 32, 33, 34 and 35. The latter are of the nature of end flaps and thus constitute means for closing the end of the compartment at the rear of the cabinet; in addition, they act as reinforcing elements resisting collapse of the erected shell. Opposed to them; that is to say, on the opposite side of the blank as seen in Figure 4, are three more or less rectangular extensions 36, 37 and 38 respectively separated from panels 26, 21 and 28 by double score lines *i*, *j* and *k*. Like extensions 32, 33, 34 and 35, extensions 36, 37 and 38 are of substantially the same transverse dimensions as the panels with which they are associated; however; they may be and in the interests of conserving material preferably are considerably shorter than extensions 32, 33, 34 and 35 in the direction of the intended longitudinal axis of the shell. Extension 36 is rectangular in shape; extension 37 is of modified rectangular shape, having appendages for forming the drawer stops as hereinafter explained; and extension 38 has a triangular cut-away portion defined by an angled edge 39 intended to mate with angled edge 31 on reinforcing panel 29. Extensions 36, 37 and 38 on side panel 26, top panel 27 and side panel 28, respectively, are of the nature of reinforcing elements and when the shell is erected go to make up an inwardly extending cuff-like portion corresponding to the three-sided cuff-like portions 20, 21 and 22 shown in Figure 2.

Score lines *e*, *f*, *g* and *h* and double score lines *i*, *j* and *k*, like score lines *a*, *b*, *c* and *d*, are on the inside or near side of the blank as seen in Figure 4.

Extension 37 on top panel 27 is provided with two slots 40, preferably of generally rectangular shape, which are cut by means of a die out of the stock of which extension 37, top panel 27 and the blank as a whole are formed. Adjoining each such slot 40 is an oblong appendage 41 separated from extension 37 by a score line *l'* and divided by a score line *l''* into two sections, 42 and 43. Oblong appendages 41 are slightly narrower in a transverse direction than slots 40 in extension 37 and, in the direction of the longitudinal axis of the shell, somewhat longer than they are wide. When reversely folded on score lines *l'* and *l''*, oblong appendages 41 form the drawer stops 17, 18 and 19 which appear in Figures 1, 2 and 3 of the drawings.

The blank is preferably further provided with a plurality of stacking recesses, the same preferably taking the form of circular openings 45 and 46 in bottom panel 25. Ordinarily, there will be two pairs of such recesses arranged as shown; viz., a pair of recesses 45 toward the rear of bottom panel 25 and, in axial alignment with them, a pair of recesses 46 near the forward end of the same panel. Not only are stacking recesses 45 and 46 in alignment in a direction paralleling the longitudinal axis of the shell but where two pairs are provided with stacking re-

cesses and arranged symmetrically in such manner that lines *X*—*X* and *X'*—*X'* drawn through or connecting the two centers of each pair will extend perpendicularly to the longitudinal axis of the shell.

In order to provide stacking lugs in top panel 27 corresponding in number to and located for later registry with stacking recesses 45 and 46 in bottom panel 25, tabs 47 and 48 are incised in top panel 27. Tabs 47 and 48 preferably take the form of circular segments which in shape are somewhat greater than semi-circles; that is to say, the arc making up the curved portion of the perimeter of the tab corresponds to an angle greater than 180°. Tabs 47 and 48 thus are so formed that they are not completely severed from the stock of which top panel 27 is formed; instead, they are scored along the chords as at *m* and *n*. Like stacking recesses 45 and 46, they are in alignment with each other in a direction paralleling the longitudinal axis of the shell to be formed from the blank. They are also in alignment perpendicularly to the longitudinal axis of the shell in a manner analogous to the lateral alignment characterizing stacking recesses 45 and 46.

However, as indicated in Figure 4, lines *Y*—*Y* and *Y'*—*Y'* connecting the centers of the arcs defining tabs 47 and 48 are not extensions of but are displaced relative to lines *X*—*X* and *X'*—*X'* connecting the centers of stacking recesses 45 and 46. Although otherwise in the same relative position in top panel 27 as stacking recesses 45 and 46 in bottom panel 25, tabs 47 and 48 are offset inwardly from the two ends of the shell. Thus with tabs 47 and 48 in the positions in which they are formed; that is to say, not folded over out of the plane of the blank, there is imperfect potential registry between stacking recesses 45 and tabs 47 on one hand and stacking recesses 46 and tabs 48 on the other.

In describing the manner of erection of the shell from the blank, it will be assumed that the first step in the sequence of operations is to bend tabs 47 and 48 on score lines *m* and *n* in a direction away from the inside or near side of the blank until they are folded against the outside or far side of the blank in the position indicated in dotted lines in Figure 5. Upon being bent into this position, tabs 47 and 48 leave behind them residual openings 49 and 50 corresponding in size and shape to the tabs themselves. After the tabs 47 and 48 have been bent through an angle of 180° into parallelism with the blank, tabs 47 and 48 are fastened in position on the outside or far side of the blank as seen in Figures 4 and 5 by any suitable means. Glue may be used for the purpose, but it is preferred to staple the tabs to the blank by heavy steel staples, which can be done in known fashion.

When tabs 47 and 48 have been folded back and stapled in place in the manner described, lines *Z*—*Z* and *Z'*—*Z'* connecting the respective centers as relocated (Figure 5) are necessarily nearer the ends of the shell than were lines *Y*—*Y* and *Y'*—*Y'* connecting the same centers as originally located (Figure 4). Assuming that dimensions and proportions have been suitably related, lines *Z*—*Z* and *Z'*—*Z'* when viewed in plan, as in Figure 5, will constitute prolongations of lines *X*—*X* and *X'*—*X'* of Figure 4; i. e., the lines joining the centers of the stacking recesses in bottom panel 25. Thus when the shell is assembled, tabs 47 and 48 will overlie stacking recesses 45 and 46. In consequence, two like

shells are properly aligned when the stacking lugs on the lower shell are disposed within the stacking recesses of the upper shell.

The tabs 47 and 48 having been folded outward to form stacking lugs, extensions 36, 37 and 38 are folded inward on score lines *i*, *j* and *k* into the position shown in Figure 5, in which these extensions and their associated parts overlie the blank on the inside or near side as seen in Figures 4 and 5. Inasmuch as score lines *i*, *j* and *k* are double score lines, they produce a more attractive and somewhat bulkier edge than if single score lines were used: this is desirable in view of the fact that the edge so formed is at what is to be the forward end of the shell. Extensions 36, 37 and 38 may be glued to the blank but preferably are stapled in place by heavy steel staples as indicated in Figure 5. In either case, however, appendages 41 are not affixed to the blank in the position which they assume after extension 37 is folded over and fastened in place; instead, they are left free for subsequent reverse folding to form the drawer stops.

This is done by folding appendages 41 on score lines *l'* into approximate perpendicularity to the blank in an angular direction opposite to the angular direction in which extensions 36, 37 and 38 are folded in order to locate them in their intended position. Thereafter, sections 43 of appendages 41 are further folded on score lines *l''* in the same angular direction as appendages 41 until the ends of sections 43 have been brought into proximity to slots 40 in extension 37. Thereupon the ends of sections 43 are manually inserted and held in slots 40, whereupon sections 43 are stapled or otherwise affixed to top panel 27. This gives the configuration shown in Figure 3, in which long section 43 is toward the forward end of top panel 27 and short section 42 lies to the rear substantially at right angles to the longitudinal axis of the shell. A strong, rigid drawer stop is thereby provided, such drawer stop resembling a triangular prism in appearance.

All of the folding accomplished up to this time, including the folding of flaps 47 and 48, the folding of extensions 36, 37 and 38 to form reinforcing means, and the reverse folding of sections 42 and 43 of appendages 41, is at right angles to corrugations 23 of the blank. Thereafter the blank as a whole is folded upon itself in the manner indicated in Figure 6; i. e., parallel to the corrugations 23 of the blank. Bottom panel 25 and top panel 27 will extend horizontally or substantially horizontally, while side panels 26 and 28, together with reinforcing panel 29, will extend perpendicularly to them. Right side panel 28 is brought into position outside reinforcing panel 29 in such manner that upright edge 30 of reinforcing panel 29 mates with the upright or near edge of extension 38 and angled edge 31 of reinforcing panel 29 mates with angled edge 39 of extension 38, all as shown in Figure 2.

The net result is to make possible a self-reinforced front end construction characterized by a cuff-like reinforcing element (20, 21, 22) extending around the greater part, but not all, of the forward end of the shell. Reinforcing panel 29 extends back along the side of the shell to the rear thereof, adding rigidity as a result of the fact that it overlaps right side panel 28 from top to bottom and from one end of the shell to the other. With these parts in this position, right side panel 28 is stapled to reinforcing panel 29, although, if desired, it may be affixed thereto by gluing or some similar operation.

These several steps having been performed, extensions 32, 33, 34 and 35, which as already pointed out serve both as reinforcing elements and as end flaps, are brought together and closed upon each other in any convenient manner, after which they are stapled, glued or otherwise fastened to each other to form the means closing the rear end of the shell.

Notwithstanding the fact that the description 10 of the invention up to this point has contemplated the use of corrugated fiber board in the blank, it is apparent that fiber board of non-corrugated construction, as well as various other fibrous and non-fibrous materials, may be employed instead. 15 Where fiber board is used, the shell preferably is impregnated chemically after being at least partially erected, as, for example, by dipping the shell in a sulphur bath, the sulphur serving as an infrofying agent, allowing it to drain, and drying it 20 at elevated temperatures: this treatment serves to harden the fiber board, providing a rigid structure which will not readily collapse under load. The beneficial effects of such treatment are enhanced where, as in the preferred embodiment 25 of the invention, the fiber board has internal corrugations extending parallel with rather than at right angles to the longitudinal axis and major fold lines of the shell, this for the reason that the path of travel of the impregnant within the corrugations may then be of maximum length.

Although it is practicable to form the completed shell by performing the various steps in the order in which they have been described, it is feasible to form the completed shell by carrying out the 30 same steps in other sequences. Instead of first forming the stacking lugs and thereafter forming the reinforcing cuff and drawer stops, it is equally practicable to form the reinforcing cuff and drawer stops first, following this operation by 35 the operation of forming the stacking lugs. If desired, either operation or both operations may be deferred until after the shell has been erected by folding the blank upon itself and stapling the right side panel to the reinforcing panel at the opposite end of the blank. The step of closing the rear end of the erected shell will not be ordinarily carried out until after the rear stacking lugs have been formed, this in order to permit needed access to the interior of the shell in 40 stapling the rear stacking lugs to the top panel.

The completed shell, having first been provided with a cooperating drawer, may be used alone; i. e., independently of other shells, or may be stacked with one or more like shells as indicated in Figures 1 and 2. The coaction between 45 the stacking recesses in the bottom panel of one of the upper shells and the stacking lugs in the top panel of one of the lower shells is illustrated in Figure 7, which is a partial vertical section paralleling the longitudinal axes of the two shells. 50 As there indicated, a self-reinforced upper shell A having in bottom panel 25' two aligned stacking recesses 45' and 46' overlies and cooperates with top panel 27' of a self-reinforced lower shell B. In addition to reinforcing elements 36' and 37', the latter has two tabs folded back upon and 55 stapled to top panel 27' to form stacking lugs 47' and 48' as previously described, leaving tab openings 49' and 50'. As is evident from Figure 60 7, stacking lugs 47' and 48' register with and project upward into but do not fill stacking recesses 45' and 46' in bottom panel 25' of shell A. Because stacking lugs 47' and 48' project oppositely to each other, take the form of sectors with 65 arcs greater than 180°, and are duplicated on the 70 75

opposite side of the two shells, sliding movement between the two shells, whether lateral or axial, is effectively precluded.

When the shells are equipped with drawers, as will usually be the case, the drawers are preferably of construction analogous to that of the shells; that is to say, they will ordinarily be of self-reinforced corrugated fiber board. If so, they will be found to lend themselves to movement without binding over the cooperating interior surfaces of the respective shells. By means of drawer stops 17, 18 and 19 (Figure 2), each of which functions as illustrated in Figure 1, the drawers are held against removal by inadvertence. If, however, the drawer is in the position shown in Figure 1 and it is desired to withdraw it altogether, it is only necessary to grasp the outer end of the drawer, elevate it sufficiently to free the drawer of drawer stop 18, and remove the drawer. Re-insertion of the drawer is accomplished by a reversal of the latter series of steps.

It is intended that the patent shall cover, by summarization in the appended claims, whatever features of patentable novelty reside in the invention.

What is claimed is:

1. A fiber board shell for a filing cabinet or the like comprising interconnected top, bottom and side walls; reinforcing means extending interiorly of the shell from the forward end thereof, the interiorly extending portion of the reinforcing means being integral with and attached to the top of the shell on the lower face thereof; and, formed integrally with the interiorly extending portion of the reinforcing means at a point near the forward end of the shell, a drawer stop formed as a hollow prism the longitudinal axis of which runs transversely of the longitudinal axis of the shell, the rear face of said hollow prism extending substantially at right angles to and having an edge that coincides with the rear edge of the interiorly extending portion of the reinforcing means.

2. A fiber board filing cabinet shell as in claim 1 in which the interiorly extending portion of the reinforcing means is provided with an oblong appendage of tab-like proportions which, to impart to the drawer stop its hollow form, is bent forward into contact with the body of the interiorly extending portion of the reinforcing means.

3. A fiber board filing cabinet shell as in claim 2 in which the forward end of the tab-like appendage is received within a slot in the body of the interiorly extending portion of the reinforcing means.

4. For a filing cabinet or the like, a chemically impregnated corrugated fiber board shell that is substantially longer from front to rear than it is in any other direction comprising interconnected top, bottom and side panels in which, in order to hold down the number of interruptions in the corrugations, the direction of the corrugations in said top, side and bottom panels parallels the longitudinal axis of the shell; means closing the rear of the shell; and formed integrally with and as an extension of said panels

at the forward end of the shell, an interiorly extending reinforcement tending to resist collapse of the shell under load, the impregnant taking the form of a sulphur-base introfying agent that serves to harden the fiber board of which the shell is constructed.

5. A fiber board shell formed from a blank of generally rectangular shape that is scored to define at least four principal panels corresponding to the top, bottom and side walls of the shell; a plurality of extensions of the nature of end flaps attached to the blank on one side thereof, said extensions being formed integrally with but scored to separate them from said panels; a plurality of extensions of the nature of reinforcing elements attached to the blank on the opposite side thereof, said extensions being formed integrally with but scored to separate them from said panels; and, incised in one of said panels, being 10 formed integrally with the blank along their chords to make it possible to fold them outward through an arc of 180 degrees into contact with the exposed surface of the shell for cooperation 15 with generally semi-circular stacking recesses in 20 another shell.

6. A fiber board shell for a filing cabinet or the like comprising interconnected top, bottom and side walls; means at the top of the shell forming generally semi-circular stacking lugs, said 30 stacking lugs being fastened to the top of the shell; means at the bottom of the shell forming stacking recesses; integrally formed reinforcing means extending interiorly of the shell from the forward end thereof, the interiorly extending portion of said reinforcing means being attached to the lower face of the shell; and, formed integrally with the interiorly extending portion of the reinforcing means, a drawer stop formed as a hollow prism the longitudinal axis of which extends transversely of the longitudinal axis of the shell, said drawer stop having a part located at least as far forward of the shell as the stacking lugs which part depends below and assumes a 35 position substantially at right angles to the body 40 of the interiorly extending portion of the reinforcing means.
